MARTIN A. POWERS, OF WINCHESTER, MASSACHUSETTS, ASSIGNOR OF ONE-HALF TO CHAS. H. STEHLING CO., OF MILWAUKEE, WISCONSIN, A CORPORATION OF WISCONSIN.

UNHAIRING-MACHINE.

No. 894,050.

Specification of Letters Patent.

Patented July 21, 1908.

Application filed October 28, 1907. Serial No. 399,456.

To all whom it may concern:

Be it known that I, MARTIN A. POWERS, a citizen of the United States, residing at Winchester, county of Middlesex, and State of Massachusetts, have invented an Improvement in Unhairing-Machines, of which the following description, in connection with the accompanying drawing, is a specification, like letters on the drawing representing like parts.

This invention relates to unhauling machines, and has for its principal object to provide a novel form of gripping device for gripping and feeding the hide while it is acted on by the knife.

I will first describe one embodiment of my invention and then point out the novel features thereof in the appended claims.

In the drawings, Figure 1 is a side view of a machine embodying my invention; Fig. 2 is a vertical central section thereof; Fig. 3 is a front view of the machine with a portion broken out; Fig. 4 is a detail of the clutch for operating the machine.

25 2 is a fixed framework which may have any suitable shape adapted to support the operative parts of the machine. Mounted on this framework in suitable bearings is a rotary knife 3 which operates to cut the hair from the hide. The knife may be driven by a suitable pulley 4 which is fast on one end of the shaft of the knife. Pivoted to the frame 2 is a swinging frame 5 which carries the presser-roll 6 and the feed roll 7. The 30 presser-roll may have any suitable or usual construction, and is shown as yieldingly mounted in its bearings, it being held in normal position by suitable springs 84. This presser-roll is arranged to hold the hide 35 against the knife while the hair is being cut therefrom, all as usual in machines of this character. The swinging frame 5 is arranged to be swung to the left, as shown in Fig. 1 and in dotted lines Fig. 2, so as to permit a hide 40 to be placed over the feed roll 7, and when a hide has been so placed, the frame is swung to the right into the full line position, Fig. 2, to bring the hide into position to be acted on by the knife 3.

45 50 The parts thus far described are or may be of any suitable or usual construction and form no part of my present invention.

In my improved machine the hide is drawn through the machine by means of gripping 55 or feeding rollers 7, 8, 8. The roller 7 is

mounted on the swinging frame 5, as above stated, but the two rollers 8 are mounted in fixed bearings 9 carried by the frame 2, said rollers preferably being yieldingly sustained in their bearings and held in their normal 60 position by springs 10. The roller 7 is provided on its periphery with a plurality of longitudinally-extending recesses 11, and the two rollers 8 are provided with correspondingly-shaped projections 12 which extend longitudinally thereof and are adapted to enter the recesses 11 as the rollers rotate.

In the preferred embodiment of my invention the cross-sectional shape of the bottom of the grooves 11 is the arc of a circle, and 70 the projections 12 are also circular in cross-sectional shape, the curvature of them being such as to substantially fit that of the grooves.

I have herein shown the roller 7 as having 75 six grooves 11 and each of the rollers 8 as having three longitudinal projections 12.

When the frame 5 is swung forwardly, as shown in full lines Fig. 2, and the rollers 7, 8, 8, are rotated, the projections 12 on the 80 rollers 8, 8 will enter the grooves 11 on the roller 7, as plainly seen in Fig. 2. The two rollers 8 are geared so as to rotate together and are so positioned relative to each other that they coöperate alternately with the roller 85 7, by which I mean that when a projection on one roller 8 is co-acting with the roller 7, the projections on the other roller 8 are out of engagement with the roller 7. By giving the feeding rollers 7, 8, 8, this construction, a 90 very firm grip on the hide is secured which will effectively draw it through the machine without danger of slipping.

The two rollers 8 may be made in any suitable way. I have herein shown the projections 12 as being formed of sections of tubing which are supported on the shaft 13 of said roller at proper distances by arms 14.

For rotating the gripping rollers I have provided the following mechanism: Fixed on 100 the shaft of the knife 3 is a gear 15 which is adapted to mesh with a gear 16 supported in a suitable bracket 62 fixedly carried by the main frame 2. Rigid with the gear 16 is a gear 17 which is adapted to mesh with a gear 105 18 fast on the shaft 19 of the roller 7. These gears may all be situated outside of the frame 2. The shaft 19 of the roller 7 has fast thereon a gear wheel 20 which is adapted to mesh with a similar wheel 21 fast on the shaft 13 of 110

the upper roller 8 and the two rollers 8 are connected together by a suitable sprocket chain 22 so that they rotate in unison and in the same direction. When the swinging frame 5 is swung into the position shown in Fig. 1 the gear 18 is carried out of mesh with the gear 17 and the gear 20 is also carried out of mesh with the gear 21 so that the feeding rollers will be idle, the only rotating parts being the positively driven knife and the gears 15, 16 and 17. The hide to be unhaired is thrown over the feeding roller 7 when the frame is swung into its dotted line position, Fig. 2, said hide hanging down between the presser-roller 6 and the knife 3. When the frame 5 is swung into the full line position, Fig. 2, the gear 18 is brought into mesh with the gear 17 and the wheel 20 is also brought into mesh with the wheel 21, and the gripping rollers will then be set in rotation thereby to feed the hide through the machine as will be obvious. I have also provided means for automatically swinging the frame 5 from the full to the dotted line position and vice versa. As herein shown said frame 5 has an arm 26 extending therefrom at each end of the machine, each of which arms carries a pinion 27 that is adapted to mesh with a cam gear 28. The two cam gears are situated at either end of the frame 2 and each is pivoted thereto at 29 and has pivotal connection with a link 30 which extends to a crank 31. One of the cranks 31 has a gear 310 thereon which meshes with a pinion 32 carried on a cross shaft 33 supported by the frame. This arrangement is such that when the cranks 31 make one half revolution sufficient to swing the cam gears 28 upwardly, said gears by acting on the pinions 27 will throw the frame 5 forwardly into the full line position Fig. 2, while when the cranks 31 make the other half revolution thereby to swing the cam gears 28 downwardly, the frame 5 is permitted to swing backwardly either under the influence of suitable springs or by gravity. The gears 32, 310, are two to one gears so that each complete rotation of the shaft 33 will give the cranks 31 a one-half rotation.

50 I have provided herein a suitable means for driving the shaft 33 which will bring said shaft to rest after it has made each complete revolution so that when the machine is started with the frame 5 thrown back into the dotted line position, Fig. 2, the shaft 33 and cranks 31 will be brought to rest after said cranks have made their half revolution sufficient to throw the frame 5 into its upright position, and similarly after the hide has been fed out from the machine and the shaft 33 is set in rotation again, the cranks 31 will be brought to rest as soon as the parts have been swung into the dotted line position Fig. 2.

65 While any suitable one-revolution clutch

might be employed, I have herein shown one which comprises a sleeve 36 rigid with the pinion 32 and having pivoted thereto a radially-extending arm 37 which is adapted to engage any one of a plurality of notches 38 in a disk 39 that is loosely mounted on the shaft 33. Said disk has a hub 40 which carries a sprocket wheel 41, and said sprocket wheel is driven by a chain 42 which passes around a sprocket wheel 43 fast on stud 80 which supports the gears 16 and 17. Since the said gears are running continuously the sleeve 40 and the clutch member 39 will be running continuously. So long as the arm 37, which constitutes the other clutch member, is held out of engagement with any of the notches 38, the clutch will be inactive, but as soon as said arm is permitted to engage in any one of the notches, the clutch will be rendered active and the crank disk 31 will be set in operation. The arm 37 is backed by a spring 45 tending to force it toward the disk 39 and when the parts are at rest and the clutch is disengaged, said arm is held out of engagement with the disk 39 by a cam ledge 47 which is carried by an arm 48 pivoted to the frame of the machine at 49. This arm has connected thereto a flexible connection 50 which runs over a direction pulley 51 and leads to a treadle 52 which for convenience is herein shown as loosely supported on the shaft 33. When the treadle is depressed, the arm 48 is elevated, thereby carrying the cam ledge 47 out of engagement with the arm 37, as shown in Fig. 4, and permitting the spring 45 to throw said arm 37 into engagement with the disk 39. The clutch is then started in operation and if the treadle is released as soon as the clutch is in operation, the lever 48 will drop into the full line position Fig. 1, thereby bringing the cam ledge 47 into the path of movement of the arm 37 as the clutch completes its first rotation so that as said arm 37 engages the cam ledge, it will be thrown to the right Fig. 3 out of engagement with the disk 39 thus disengaging the clutch.

While I have only described one embodiment of my invention I do not wish to be limited thereto.

Having fully described my invention, what I claim as new and desire to secure by Letters Patent is:—

1. In an unhairing machine, the combination with a rotary knife, of a swinging frame, a feeding roller carried thereby, said roller having longitudinal grooves and a coöperating feeding roller mounted in fixed bearings, said last-named roller having longitudinal projections to enter the grooves of the grooved roller.

2. In an unhairing machine, the combination with a fixed frame, of a rotary knife mounted thereon, a pair of feeding rollers also mounted thereon, each feeding roller

having projections extending longitudinally thereof, a swinging frame pivoted to the fixed frame, and a feeding roller carried thereby and having longitudinally-extending grooves.

3. In an unhairing machine, the combination with a fixed frame, of a rotary knife mounted thereon, a pair of feeding rollers also mounted thereon, each feeding roller having projections extending longitudinally thereof, which projections are convexly curved in cross section, a swinging frame pivoted to the fixed frame, and a feeding roller carried thereby and having longitudinally-extending grooves which are concavely curved in cross section.

4. In an unhairing machine, the combination with a fixed frame, of a rotary knife mounted thereon, a pair of feeding rollers also mounted thereon, each feeding roller having projections extending longitudinally thereof, which projections are convexly

curved in cross section, a swinging frame pivoted to the fixed frame, a feeding roller carried thereby and having longitudinally-extending grooves which are concavely curved 25 in cross section, and means to rotate the first-named feeding rollers so that they act alternately on the last-named feeding rollers.

5. In an unhairing machine, the combination with a fixed frame, of a rotary knife carried thereby, a swinging frame carrying a feeding roller and a presser roller, said frame having an arm provided with a gear, a pivoted cam gear adapted to mesh with said gear, and means for operating the cam gear. 30 35

In testimony whereof, I have signed my name to this specification, in the presence of two subscribing witnesses.

MARTIN A. POWERS.
